Primary Examiner — Gino Colan(74) *Attorney, Agent, or Firm* — Warner Norcross + Judd, LLP(57) **CLAIM**

The ornamental design for a discharge valve assembly, as shown and described.

DESCRIPTION

FIG. 1 is a top perspective view of a discharge valve assembly showing my new design;

FIG. 2 is a bottom perspective view thereof;

FIG. 3 is a right side elevation view thereof, the left side elevation view, front elevation view and rear elevation view being a mirror image thereof;

FIG. 4 is a bottom view thereof; and,

FIG. 5 is a top plan view thereof.

The broken lines shown in the figures are included for the purpose of illustrating environment and form no part of the claimed design.
